UNITED STATES PATENT OFFICE.

HENRY C. THOMPSON, OF HARTFORD, CONNECTICUT, ASSIGNOR TO THE HALL-THOMPSON COMPANY, OF HARTFORD, CONNECTICUT, A CORPORATION OF CONNECTICUT.

AUTOMOBILE-TOP PATCH.

1,211,642.

Specification of Letters Patent.

Patented Jan. 9, 1917.

Application filed August 9, 1916. Serial No. 114,033.

To all whom it may concern:

Be it known that I, HENRY C. THOMPSON, a citizen of the United States, residing at Hartford, in the county of Hartford and 5 State of Connecticut, have invented certain new and useful Improvements in Automobile-Top Patches, of which the following is a specification.

This invention relates to what I shall for 10 convenience term "an automobile top patch". While the article in question is especially adapted for use by automobilists for which reason the title selected has been given, it is of equal utility in other connections, for 15 instance for effecting repairs in tops of carriages and other vehicles.

It is a matter of fact that small holes are 20 burned, chafed and otherwise formed in the mohair cloth or pantasote tops of automo- biles. At the present time to put such tops in proper condition, it is sometimes neces- 25 sary to entirely replace the fabric and at others to remove a panel and substitute for it a new one. I provide means of a simple 30 nature which can be readily, quickly and easily applied to cover these holes in such manner that they will be permanently closed and the repairs unnoticed, the top with such patch or patches being practically as good 35 as in its original condition. The patch is of such character that it does not require the aid of an expert to apply it.

In the drawings accompanying and forming part of the present specification I have 40 shown in detail one of the many convenient forms of structural embodiment of the in- vention which I will set forth in detail in the following description. I do not restrict myself to this precise disclosure; I may de- 45 part therefrom in several respects within the scope of the invention defined by the claim following said description. It is a matter of fact that I only show one kind of struc- ture, but it is made in different shapes. I 50 might observe that the shape under ordi- nary conditions is not a matter of great im- portance.

Referring to said drawings: Figure 1 is 55 a face view of a patch involving the in- vention. Fig. 2 is a rear view of the same with the protective strip partly removed. Fig. 3 is a transverse section on a larger scale on the line 3-3 of Fig. 1. Fig. 4 is

a view corresponding to Fig. 1 of a patch of another shape.

The patch preferably involves in its make- 55 up a body or base member of suitable fabric, mohair, pantasote and leather being well adapted for the purpose. This patch or body member of mohair or other desired ma- 60 terial is preferably provided on its apply- 65 ing face with a suitable adhesive, one kind of which will be hereinafter mentioned. On the adhesive face of the body or patching member is applied a protective part which 65 may be of any suitable material such for instance as muslin.

With the foregoing general observations I will first refer in detail to Figs. 1, 2 and 3. The patch shown in these views is in the 70 form of an elongated, practically rectangular strip 2 of composite construction. Said strip 2 as represented comprises in its make-up a base, body or patching member as 3 which as I have already noted is of some 75 suitable fabric. This flexible body or patching member is imperforate throughout its entire extent, although this may not always be necessary. It is certainly desirable, how- 80 ever, that that part of the body or patching member which is used for repairing should be of this nature. This body has applied to it a suitable adhesive as 4, the adhesive cov- 85 ering the entire back face of the body and constituting the agent by which the patch- 85 ing member can be united with a top or simi- 90 lar part to permanently cover and thus re- pair a rent or opening therein. Connected with the coated or cemented face of the body or patching member is a protective part as 90 the strip 5. As I have already remarked this strip 5 may be of muslin or holland which are merely two of several materials suitable for the purpose. The protective piece or cover 5 as shown is coextensive with 95 the coated surface of the body or patching member, the two members being united by pressure or otherwise to produce the com- posite or laminated strip.

The adhesive which I prefer to employ is 100 of a highly advantageous type, being self- vulcanizable by natural heat as distin- guished from artificial heat; obviously the sun's rays best answer in this connection. The adhesive coating consists of pure rubber 105 gum without the use of any reclaimed rub-

ber; it is mixed with the necessary sulfur and other agents requisite to insure vulcanization. Said pure rubber in sheet form is compressed on the backing or patch member as 3 and impregnates or is incorporated into the pores or interstices of the backing or patching member, the consequence being that the two are interlocked. After they are associated by pressure the protective cover or piece 5 is applied.

10 The strip can be carried in a box or in the kit of an automobilist. It will be supposed that there is a hole to be repaired. In this case the following procedure may be 15 adopted: First the user will cut from the strip 2 the necessary length to make the requisite repair. When this is done the facing or protective piece 5 will be removed as illustrated in Fig. 2. The gum or rubber 4 will 20 then be softened by gasolene or similar solvent or ordinary cement may be applied to the rubber coating 4 to make the same sufficiently soft to adhere to an object. When this is accomplished the coating 4 is placed 25 on the fabric of the cover around the hole to be repaired and pressed firmly against the cover or top by the fingers or otherwise. By using the pure rubber gum I find that the patch can be permanently held in place by 30 being naturally vulcanized as I term the

process as by the sun's rays as already observed. Natural heat as will be clear without the sun can be utilized.

While as I have stated the patching member may be of any one of several materials, 35 mohair best answers this purpose, because the soft rubber gum can be so intimately associated with it as to make a joint of maximum strength.

In Fig. 4 the patch 6 is constructed and 40 used exactly as hereinbefore described, the only difference as will be clear, being one of shape. This patch 6 is in the form of a plicated disk comprising a body or patching member provided with a pure rubber gum 45 adhering thereto and the protective coating, all as already set forth.

What I claim is:

An automobile top repair patch comprising: 50 a mohair body provided on one side with an adhesive in the form of a rubber gum vulcanizable by natural heat, the rubber gum being compressed into the mohair body.

In testimony whereof I affix my signature in the presence of two witnesses.

HENRY C. THOMPSON.
